GAME CABINET

Ripley Wade, Mobile, Ala.

Application March 14, 1949, Serial No. 1,386

Term of patent 7 years

(Cl. D34—15)

To all whom it may concern:

Be it known that I, Ripley Wade, a citizen of the United States, residing at Mobile, in the county of Mobile and State of Alabama, have invented a new, original, and ornamental Design for Game Cabinet of which the following is a specification, reference being had to the accompanying drawing, forming a part thereof.

The dominant features of the design reside in the portions shown in solid lines in the drawings.

I claim:

The ornamental design for a game cabinet, as shown and described.

RIPLEY WADE.
